FIG. 5 is a left side view of FIG. 1;

FIG. 6 is a top view of FIG. 1;

FIG. 7 is a bottom view of FIG. 1;

FIG. 8 is a front perspective view of the electroporation device, according to an embodiment;

FIG. 9 is a front view of FIG. 8;

FIG. 10 is a back view of FIG. 8;

FIG. 11 is a right side view of FIG. 8;

FIG. 12 is a left side view of FIG. 8;

FIG. 13 is a top view of FIG. 8;

FIG. 14 is a bottom view of FIG. 8;

FIG. 15 is a front perspective view of a portion of the electroporation device of FIG. 8;

FIG. 16 is a front view of FIG. 15;

FIG. 17 is a back view of FIG. 15;

FIG. 18 is a right side view of FIG. 15;

FIG. 19 is a left side view of FIG. 15;

FIG. 20 is a top view of FIG. 15;

FIG. 21 is a bottom view of FIG. 15;

FIG. 22 is a front perspective view of a portion of the electroporation device of FIG. 8;

FIG. 23 is a front view of FIG. 22;

FIG. 24 is a back view of FIG. 22;

FIG. 25 is a right side view of FIG. 22;

FIG. 26 is a left side view of FIG. 22;
